UNITED STATES PATENT OFFICE.

ABRAHAM W. ROSEN, OF NEW YORK, N. Y.

DESIGN FOR A COMBINED MATCH STAND AND ASH TRAY.

61,119.

Specification for Design.

Patented June 20, 1922.

Application filed May 28, 1921. Serial No. 473,405. Term of patent 7 years.

To all whom it may concern:

Be it known that I, ABRAHAM W. ROSEN, a citizen of the United States, residing at 610 Broadway, New York city, in the county of New York and State of New York, have invented a new, original, and ornamental Design for a Combined Match Stand and Ash Tray, of which the following is a specification.

Fig. 1, is a perspective view of the combined match stand and ash tray.

Fig. 2, is a plan view of the combined match stand and ash tray showing the new design.

I claim:

The ornamental design for a combined match stand and ash tray, as shown.

In testimony whereof I affix my signature.

A. W. ROSEN.
